UNITED STATES PATENT OFFICE.

FREDERICK MEYER, OF LONDON, ENGLAND.

EVAPORATING APPARATUS.

SPECIFICATION forming part of Letters Patent No. 780,612, dated January 24, 1905.

Application filed November 30, 1903. Serial No. 183,217.

To all whom it may concern:

Be it known that I, FREDERICK MEYER, a subject of the King of Great Britain and Ireland, and a resident of London, England, have 5 invented a new and useful Improvement in Evaporating Apparatus, of which the following is a specification.

This invention relates to apparatus used for the condensation or concentration by evaporation of saccharine syrups, brine, or other liquids; and its leading object is to greatly expedite the process of evaporation. More particularly, its objects are to insure the most effective distribution of the liquid with reference to the heated evaporating-surfaces, to prevent any considerable accumulation of the liquid in contact with such surfaces, to provide for effectively controlling the operation, and to employ a minimum of machinery for 20 producing the desired results.

The invention consists in certain novel combinations of parts hereinafter set forth and claimed, including the combination with suitable accessories of a "sparger" or revolving 25 sprinkler inside each evaporating vessel, and also a pump attached at the lowest point of each vessel or in any other suitable position, the same serving, respectively, to evenly distribute the syrup or other liquid over the 30 evaporating-surfaces and when necessary to pump back the syrup or other liquid through the sparger or sprinkler and to redistribute the same in the same vessel for further concentration or condensation or alternatively to 35 pump the same through the sparger or sprinkler of the succeeding vessel.

I preferably employ an automatic sparger or sprinkler such as is generally used in the process of brewing and which is thus of demonstrated practicability. This form of sparger or sprinkler revolves automatically by the pressure of the syrup or other liquid as it leaves the perforated arms. Alternatively the "sprinkler," as it is hereinafter termed, 45 may be made to revolve by gearing or other suitable means.

I preferably employ a series of evaporating vessels diminishing in size from the first to the last of the series and having the necessary 50 extent of evaporating-surface within each ves-

sel formed by vertical tubes heated by steam in the first vessel and in the succeeding vessel or vessels by the hot vapor from the preceding vessel. As the sprinklers revolve the liquid escaping from the perforations therein 55 is evenly distributed within the subjacent vertical tubes forming the evaporating-surfaces. When it is found that the liquid is not in a proper condition to enter the second vessel, the liquid is pumped back into the 60 sprinkler of this first vessel, which again distributes it within the evaporating-tubes for further condensation or concentration. The liquid then passes from the bottom of this first vessel through a pipe to the sprinkler in 65 the second vessel and trickles down the bare hot tubes in the drum of this vessel, and if found necessary the liquid is pumped back into the sprinkler of this second vessel, which again distributes it within the bare hot tubes 70 within the drum of the vessel for further condensation or concentration. Passing again from the bottom of this second vessel through a pipe connected to the sprinkler in the third vessel the liquid is distributed within the 75 bare hot tubes of the drum in this vessel, and should the liquid require still further condensation or concentration it is pumped back into the sprinkler of this third vessel and again distributed within the bare hot tubes 80 of this vessel from the bottom of which, supposing this vessel to be the last of the series, the liquid is finally drawn off by any suitable means. I do not limit myself to any particular number of evaporating vessels, but prefer to employ a series, as above indicated. The vapor arising from the liquid in the first vessel passes up through the top of this vessel into a pipe which is connected to the drum of the second vessel and is utilized for heating 90 the tubes in said second vessel, and in like manner the vapor arising from the liquid in the second vessel is used for heating the tubes in the drum of the third vessel of the apparatus.

The great advantage obtained in the use of a sprinkler and pump in the manner above described is that very little syrup or other liquid is kept in the body of each vessel, and by the use of a revolving sprinkler none of 95 100

the liquid can drop down an individual tube without coming in contact with the inner surface of the tube in an ideal form for film evaporation. Moreover, the ascending vapor 5 cannot carry over with it small particles of the syrup or other liquid, nor can it be recon-
10 densed by the liquid, as the latter is confined to a line represented by the arms of the sprinkler, whereas in existing systems the liquid 15 covers the tubes and many of the steam bubbles formed at the bottom are recondensed before they can rise to the surface and escape, thus detracting from the evaporating power as compared with my apparatus.

15 The improved apparatus can be applied to open-air evaporation as well as evaporation in vacuum.

Two sheets of drawings accompany this specification as part hereof.

20 Figure 1 is a sectional elevation of the im-
proved evaporating apparatus with three ves-
sels in series, as above described. Fig. 2 is
a plan view projected from Fig. 1; and Figs.
25 3 and 4 are respectively side and plan views
of one of the revolving sprinklers, on a larger
scale, illustrating its operation.

Like reference-letters indicate correspond-
ing parts in all the figures.

A, B, and C are respectively the first, sec-
30 ond, and third evaporating vessels of an ap-
paratus constructed according to the present
invention. The revolving sprinklers in the
respective vessels are shown at D, D', and D''.
Open-ended vertical tubes in the steam-drums
35 of the respective vessels are shown at F, H,
and J, and pumps attached to or connected
with the respective vessels are shown at N,
O, and P. The syrup or other liquid to be
treated enters the sprinkler D of the first ves-
40 sel by an inlet-pipe E and is discharged
through a pair of arms R, which are provided
with any number of perforations arranged so
that while the liquid is escaping through these
45 perforations the arms will revolve automatic-
ally, being supported on ball-bearings V.
The liquid is thus evenly and effectively dis-
tributed among the bare hot tubes F in the
drum of this vessel A, these tubes being heat-
50 ed by steam supplied through a neck W in the
usual manner. The steam or vapor escaping
from the liquid under treatment rises freely
at the sides of the revolving arms R, and the
sprinklers thus offer no material obstruction
55 to the escape of such vapor at any time or
from any point in the apparatus. It is some-
times found that the liquid on reaching the
bottom of the vessel A through the tubes is
not in a proper condition to enter the second
60 vessel B. It is then forced back through a
pipe S by said pump N into said sprinkler D
to be again discharged down the bare hot
tubes F in said first vessel. The liquid then
passes from said first vessel A through a pipe
65 G into said sprinkler D' in the second vessel
B, escaping from the perforated arms R of

this sprinkler down the bare hot tubes H in
the drum of said vessel B, and if found nec-
essary the liquid is forced back through a
70 pipe T by said pump O into said sprinkler D'
to be again discharged down the bare hot
tubes H in this second vessel B. The liquid
then passes from the second vessel B through
a pipe K into the sprinkler D'' in the third
75 vessel C, escaping from the perforated arms
R of the sprinkler down the bare hot tubes J
in the drum of this vessel C, and if found nec-
essary the liquid is again forced back through
a pipe U by said pump P into said sprinkler
80 D'' and again discharged down the bare hot
tubes J. The condensed or concentrated liq-
uid as it finally collects in the bottom of the
last vessel C is drawn off by a pump or other
means through an outlet-pipe Y.

The tubes F in the first vessel A are heated
by means of steam entering the drum of this
85 vessel through an inlet-pipe W, as aforesaid,
and circulating outside the tubes. In like
manner the tubes H and J in the vessels B
and C are heated by the hot vapor from the
boiling hot liquid in the vessels A and B, the
90 vapor being conveyed to the drums of these
vessels by means of pipes L and M. The va-
por or steam leaves the drums of the respec-
tive vessels in the form of condensed steam
or water by means of outlet-pipes X, X', 95
and X''.

Having thus described said improvement, I
claim as my invention and desire to patent
under this specification—

1. Apparatus for the condensation or con-
centration of liquids, such apparatus having,
in combination, an evaporating vessel, an in-
let-pipe for the liquid to be treated, a sprinkler
within said vessel in communication with said
inlet-pipe, subjacent open-ended vertical tubes
105 through which the sprinkled liquid descends,
and a heating-drum through which said tubes
extend, said tubes being at all times substan-
tially empty so as to expose substantially bare
hot evaporating-surfaces down which the li-
quid under treatment trickles, substantially as
hereinbefore specified.

2. An evaporating apparatus having, in com-
bination, an evaporating vessel provided with
a vapor-outlet, an inlet-pipe for the liquid to
115 be treated, a sprinkler in the form of revolv-
ing arms within said vessel in communication
with said inlet-pipe, subjacent open-ended ver-
tical tubes through which the sprinkled liquid
descends, a heating-drum through which said
120 tubes extend, and means for keeping said tubes
substantially empty so as to expose substan-
tially bare hot evaporating-surfaces down
which the liquid under treatment trickles, the
vapor therefrom rising freely through said
125 tubes and at the sides of said revolving arms
and through said outlet, substantially as here-
inbefore specified.

3. An evaporating apparatus having, in com-
bination, an inlet-pipe for the liquid to be
130

treated, a sprinkler in communication with said inlet for distributing such liquid, subjacent open-ended vertical tubes within which the sprinkled liquid trickles downward, a heating-drum through which said tubes extend, an inclosing vessel within the bottom of which the condensed or concentrated liquid collects, and a pump in communication with the interior of said vessel and said sprinkler for keeping said tubes substantially empty and for forcing back the liquid through the sprinkler for further treatment, substantially as hereinbefore specified.

4. An evaporating apparatus having, in combination, an inlet-pipe for the liquid to be treated, an automatically-revolving sprinkler in communication with said inlet-pipe, subjacent evaporating-surfaces upon which the liquid is distributed by said sprinkler, means for heating said evaporating-surfaces, a vessel inclosing said sprinkler and evaporating-surfaces within which the condensed or concentrated liquid collects below said surfaces, and a pump in communication with the interior of

said vessel and said sprinkler for returning 25 the liquid for further treatment, substantially as hereinbefore specified.

5. The combination of a series of evaporating vessels each of them inclosing an automatically-revolving sprinkler, in the form of 30 perforated arms for distributing the liquid, subjacent open-ended vertical tubes through which the liquid descends, a steam-drum by which said tubes are heated, a steam-pipe for supplying the drum of the first vessel, a pipe 35 connecting the drum of each succeeding vessel with the top of the preceding vessel, and pumps connecting the interior of each vessel at bottom with the superjacent sprinkler and also with the sprinkler of the succeeding vessel, substantially as hereinbefore specified.

In testimony whereof I affix my signature in the presence of two witnesses.

FREDERICK MEYER.
